his Atty;

UNITED STATES PATENT OFFICE.

JOSEPH SHAFFER, OF DAYTON, OHIO, ASSIGNOR OF ONE-HALF OF HIS
RIGHT TO JACOB A. PRITZ, OF SAME PLACE.

MANUFACTURE OF HARNESS-LOOPS.

SPECIFICATION forming part of Letters Patent No. 226,004, dated March 30, 1880.

Application filed June 26, 1879.

To all whom it may concern:

Be it known that I, JOSEPH SHAFFER, of Dayton, in the county of Montgomery and State of Ohio, have invented certain new and 5 useful Improvements in the Manufacture of Harness-Loops; and I do hereby declare the following to be a full, clear, and exact description of the same.

My invention relates to an improvement in 10 the construction of crimped or corrugated concavo-convex loops for harness, and also in the process and machinery for producing the same.

Hitherto crimped or corrugated loops for 15 harness have been made by securing or pasting a comparatively thin sheet of finished leather over a base-piece either of leather, wood, or metal, previously shaped to give the required ornamental form, and having the 20 transverse gutters or ridges formed by cutting or otherwise.

The objection to these loops so constructed, aside from the cost and care required in fitting the finishing leather upon the base-piece, is 25 the liability of the exterior finishing-leather to come off or wear through, and thus render the article unsightly.

The novelty of my invention consists in 30 subjecting a moistened piece of leather of the required thickness of the loop to the action of an elastic expansible mandrel in a concave die having transverse gutters and ridges so shaped and located as to give the requisite ornamentation and configuration.

35 It also consists in the combination, with a concave die having depressions and ridges, of an expansible mandrel actuated by suitable pressure, whereby sheets or pieces of moistened leather may be separately pressed or 40 swaged in the die to give them a concavo-convex form with suitable ornamentation, such as transverse corrugations, all as will be herewith set forth and specifically claimed.

In the accompanying drawings, Figure 1 is 45 a perspective view of the die. Fig. 2 is a sectional elevation through the line $x-x$ of Fig. 1. Fig. 3 is a side elevation of a harness-loop as constructed by my improved process.

A, Fig. 1, represents a solid block of metal 50 having a longitudinal concavity in its upper

surface, as shown, which is shaped and regulated in size to give the required form to the harness-loop.

In the present instance this channel or cavity in the block extends through from end to end, and brace-pieces B are suitably secured by bolts or screws to the ends of the block, as represented. This, however, is not essential, as the die with its end walls may be cast in one piece.

As shown in Fig. 1, the concavity is not smooth, but is crossed transversely by ridges and indentations, which give to the leather to be pressed therein a corresponding shape and ornamental finish, as seen in Fig. 3.

The style of ornamentation may be varied 65 infinitely to suit the character of the loop; and to enable the same die to produce different configurations and ornamentations extra metal bands of various shapes and sizes, such 70 as represented by C, Fig. 1, may be removably fastened, by screws or other suitable means, in the concavity.

The flat piece of leather D, of the required thickness, which is to be shaped and ornamented, is first thoroughly moistened to render it pliant and soft. It is then bent and placed in the concavity, as shown in Fig. 2. The mandrel E, Fig. 2, is then inserted between the folds of the leather, and is pressed by the 80 hand into the concavity. It is necessary that this mandrel should be expansible under pressure, in order to force the leather out into the creases and depressions of the die; and to this end I preferably construct it of stiff though 85 elastic rubber, of a single piece, and having its under portion shaped to fit somewhat loosely in the die.

With this mandrel inserted as above described, the whole is placed in any suitable 90 press, which forces the mandrel down into the die, and as the mandrel is expansible, it is forced out laterally as well as downwardly, and thus presses the moistened pliant leather into all the indentations or depressions of the 95 die. The die and its contents are left in the press until the leather is sufficiently dried and set to retain its new shape, when the pressure is removed and the leather is taken out finished, as seen in Fig. 3. The plain ends a 100

may then be either cut off or left to furnish means for attaching the article thus formed to harness.

A number of loops may be pressed at one 5 operation, and this number is only limited by the number of dies and the size of the press.

By thus pressing the loop to the required shape, and giving it its ornamentation at the same operation, a great saving of time and 10 labor is accomplished, and a much more durable article is produced.

Having thus fully described my invention, I claim—

1. The herein-described process of manufacturing loops for harness, by first moistening 15

the leather and subjecting it then to the pressure of an elastic mandrel in a die, as set forth.

2. The combination, with a concave die having ornamenting ridges or depressions, of an elastic mandrel, whereby moistened pieces of 20 leather may be pressed in the die to give them a concavo-convex form with suitable ornamentation, as set forth.

Witness my hand this 23d day of May, A. D. 1879.

JOSEPH SHAFFER.
